INFANT'S CREEPER

Joseph Astrove, New Rochelle, N. Y.

Application November 26, 1949, Serial No. 129,555

1 Claim. (Cl. 2—80)

2

1 My invention relates to an infant's creeper, more particularly to an infant's garment in the nature of overalls.

It is contemplated by my invention to provide a garment for infants and toddlers which is used protectively to cover the clothing of a young child who is beginning to crawl. Ordinary overalls having foot openings do not adequately retain their position on the limbs of the infant and provide an obstacle to dressing and diapering the child.

Known to me are the efforts to provide the side seams or crotch seams with closures, such as zippers, to facilitate the dressing operation. Such devices include foot openings and require zippers employing separators at the terminal end, which, for a squirming child, is not an inconsiderable source of annoyance and inconvenience.

In accordance with my invention, it is an object thereof to provide a creeper or overall type of garment having a front and rear panel and side seams joined by closures for speedily performing the dressing operations upon infants and young children, the actuation of the closing operation being facilitated by the inclusion of a foot enclosure, eliminating the necessity for costly and difficultly operable separators in these fastening elements.

It is a further object of my invention to provide a creeper which assures a leg covering over the clothing so that the trouser legs are not displaced from the protective position, yet permitting facile and speedy dressing operations.

To attain these objects and such further objects as may appear herein or be hereinafter pointed out I make reference to the accompanying drawing forming a part hereof, in which—

Figure 1 is a front three quarter perspective view illustrating creepers in accordance with my invention;

Figure 2 is a rear three quarter perspective view of the same;

Figure 3 is a perspective view with the front panel turned down to illustrate the quick detachability thereof;

Figure 4 is a magnified section on the line 4—4 of Figure 1.

My invention may be summarized as providing a creeper having quickly detachable shoulder straps or suspenders to permit slipping a garment over an infant's or toddler's legs, and including the features of side seams held together by quickly detachable fastening means, such as zippers, the trouser portions of which adjacent the ankles are closed by foot portions

and elastic gripping the ankles, with the closure running from the angle upwardly to the waistline. By this form of construction, the suspenders form a partial closure for the garment, the latter pulling against the restraining action of the foot portion in holding the garment stretched over the body partially. This stretching serves to align the zippers on the side seams for quickly effecting the dressing or undressing operation, and without requiring separators to join the terminal portions of the stringers for the zippers.

Making reference to the drawing, I show a creeper or garment in the form of overalls having a front panel 10 and a rear panel 11. The front panel includes sections 12 and 13 connected by the seam 14 running to the crotch 15. The front panel includes a pair of supporting tabs 16 having button holes 17, for purposes which will appear hereafter.

20 The rear panel 11 includes sections 18 and 19 connected by the seam 20 which extends into the crotch 15, previously described. A waistline hem 21 is provided with an elastic for constricting this portion. Suspender straps 22 are attached to the waistline 21 and have the terminal portions 23 formed with buttons 24. The straps are intended to be crossed over the shoulders in the well known way to engage the button holes 17.

The sections 12, 13, 18 and 19 merge into trouser leg forming extensions 25, and terminate into foot covering enclosure portions 26. Side edges 27 and 28 on the rear and front panel, respectively, are provided with stringers 27a, 28a, carrying separable fasteners or scoops which extend from the waistline portion 21 to just below the ankle at 29. A hem portion or tubular channel 30 is provided with an elastic 31, constricting or shirring the ankle forming portion of the trouser leg at the ankle just above the end of the seam. The stringers 27a and 28a attached to the edges 27 and 28 and the separable fasteners thereon are coupled by the fixed stop at the edge 29, at which portion the slider 32 begins to interlock the scoops from below the ankle position to the waistline position and forms the quickly detachable side seams 33 and 34.

To dress the infant, the sliders are shifted down to a position below the ankles, as shown in Figure 3. The leg portions then are uncovered and the foot of the child is inserted in the foot portions 26. In this position the front panel 10 and rear panel 11 are held in position by the suspender or straps 22. The child is then partially dressed as the garment is stretched in position. The garment may be closed very easily with the zippers

by drawing up the sliders along the legs. The resistance afforded by the anchoring effect of the foot forming portion 26 facilitates this closing action, especially with the suspenders holding the panels partially stretched and in alignment.

The initial interlocking of the scoops of the zippers is further facilitated as the slider is brought up above the elastic ankle portion afforded by the hem 30 and the elastic 31.

Conversely, when speedy undressing is required, actuation of the sliders downwardly is not restrained as the garment is held stretched over the infant's legs by the suspension afforded by the suspender straps and the engagement at the opposite end of the garment by the foot covering portions.

In use by the toddler or crawling child or in being carried, riding of the leg to a non-protecting position is minimized and coverage as well as speedy detachment is made possible.

Having thus described my invention and illustrated its use, what I claim as new and desire to secure by Letters Patent, is:

A creeper for infants including a front panel portion, a rear panel portion extending substantially from the waistline and terminating into leg covering sections, joined to each other at the crotch, closed foot covering portions for the ter-

5 minal portions of said leg covering sections, both side edges for each of said panels running from the waistline to below the ankle portion of said leg portions to adjacent the closed foot covering portions, separable fasteners joining both of the side edges of said panels to provide on each side a quickly separable seam from below the ankle portion adjacent said closed foot portions to the waistline, suspender means for the upper portion of said panels whereby the garment may be held in position on the infant wearer by the suspenders and closed foot portions when releasing the front panel from the rear panel so that the leg covering portions are always attached to the wearer during release of the front panel.

JOSEPH ASTROVE.
